DESIGN FOR A BREAKFAST TABLE

Lewis Garshofsky, New York, N. Y.

Application November 7, 1935, Serial No. 59,417

Term of patent 3½ years

To all whom it may concern:

Be it known that I, Lewis Garshofsky, a citizen of the United States, residing at 461 First Avenue, in the county of New York, city and State of New York, have invented a new, original, and ornamental Design for Breakfast Tables, of which the following is a specification, reference being had to the accompanying drawing, forming part thereof.

The figure is a perspective view of a breakfast table showing my new design.

I claim:

The ornamental design for a breakfast table, as shown.

LEWIS GARSHOFSKY.
